Qiang Li

(57) **CLAIM**

The ornamental design for chair with canopy, as shown and described.

DESCRIPTION

FIG. 1 is a front perspective view of chair with canopy, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1;

FIG. 10 is an enlarged detail view of area 10 in FIG. 1;

FIG. 11 is an enlarged detail view of area 11 in FIG. 2;

FIG. 12 is an enlarged detail view of area 12 in FIG. 2; and,

FIG. 13 is an enlarged detail view of area 13 in FIG. 2.

The broken lines in the drawings illustrate the portions of the chair with canopy, which form no part of the claimed design. The long dash-short dash broken lines in FIGS. 1, 2, 9, 10, 11, 12 and 13 show the boundaries of the enlargements shown in FIGS. 9, 10, 11, 12 and 13, and form no part of the claimed design.

1 Claim, 13 Drawing Sheets
